UNITED STATES PATENT OFFICE.

DOROTHY MILLER, OF KANSAS CITY, MISSOURI.

MUSICAL CHECKERBOARD.

Application filed August 14, 1922. Serial No. 581,860.

To all whom it may concern:

Be it known that I, DOROTHY MILLER, a citizen of the United States, and resident of Kansas City, county of Jackson, State of Missouri, have invented a certain new and useful Improvement in Musical Checkerboards, of which the following is a complete specification.

This invention relates to musical checker boards or the like, and has for its object to produce an interesting and instructive game played like "checkers" or an analogous game, whereby the players shall, without conscious mental effort, learn the names and positions of the lines and spaces of the musical staff, and the identification thereof on the piano key board.

More specifically, the invention has for its object to produce a game board combining the features of a checker or chess board or the like, musical staffs—preferably both treble and bass—and a piano key board adjacent and parallel with each staff, each key board section preferably comprising one white key in excess of two octaves. The game can be played in the "treble" or "bass" by two players using duplicate sets of "pieces" preferably of different colors to avoid confusion, and each set comprises "pieces" respectively lettered a, b, c, d, e, f, and g.

With the object of producing a game board of the character set forth, the invention consists in combining with a checker board or the like, the representation of opposing musical staffs and key boards, and two sets of checker "pieces", marked from a to g inclusive, to be moved as in the game of checkers or the like, until one player has captured one complete set of the "pieces" of the other, bearing the names of the "spaces" or "lines" of the musical staff, accordingly as the game is a game for "spaces" or "lines" or scales, chords, intervals, etc. It may also be a rule of the game that the player first capturing a complete set of the "pieces" of the opponent, shall be required to state when capturing a "piece" representative of a "line" or "space" as the case may be, that such piece corresponds in identification or name to a particular key of the key board, a failure to so state being penalized by the loss of the "piece" or in some other way. The special rules or penalties of the game may be varied of course, as they are merely in the interest

of requiring the players—especially children, to be mentally alert and hence more quickly and thoroughly learn the names and relations of the lines and spaces of the musical staff and the relation thereto of the piano key board.

In order that the invention may be readily understood, reference is made to the following description and appended claims, and to the drawing which represents a plan or face view of the game board.

Referring now to the drawing in detail, 1 indicates a board, preferably rectangular and provided centrally with the conventional checker board "squares" 2 and 3, augmented preferably by additional or special "king-rows" 4 at the four sides of the conventional checker board marking. Outward of the king-rows 4, and parallel therewith are representations of the piano key board as at 5, each key-board being shown as running from the letter c through two complete octaves and one additional white key of the next octave above or below.

Parallel with each key board, and appearing upon the outer sets of "squares" of the conventional checker board, are musical staffs, one parallel pair constituting treble staffs and the other pair constituting bass staffs as identified by treble and bass staff-indicating characters.

It is preferred that the first white keys at the left hand end of the key-boards parallel with the "treble" staffs, shall be marked "M C" to identify middle C, of the key-board, and that the corresponding keys at the right hand end of the key boards parallel to the bass staffs shall be similarly marked, thus indicating the position of middle c on both treble and bass staffs.

The "pieces" identified by the letters of the lines and spaces of the staff are preferably initially positioned on spaces 2 as shown and then they are used as in the game of checkers, the object of each player being to capture certain pieces, such as one set of the opponent's pieces named in accordance with the lines or the spaces of the staff, treble or bass as the case may be. If a player penetrates the opponent's king-row 4, he may crown the piece or pieces attaining such position and have the right to move in other directions as under the same conditions in the game of checkers.

The first player to capture a full set of pieces as above suggested, wins the game,

though it may be a rule that if such player fails to indicate the position on the key board of each of such pieces before making any further move, he shall forfeit the piece.

5 This, however, is a rule of play merely.

It will be obvious that many games differing in the method of play or in the character of musical instruction, may be played on this board, and that some instructive 10 games may be played wherein the staffs or the key boards are used independently of each other, but in conjunction with the squares of the board, the most satisfactory and interesting games however involving 15 the use of the squares with both staffs and key boards.

From the above description it will be apparent that I have produced a musical game board possessing the features of construction 20 set forth as desirable in the statement of the objects of the invention, and which may be modified in minor particulars within the scope of the appended claims.

I claim:

25 1. A musical game board having a rectangularly checkered face and a pair of musical staffs near opposite margins of the board, and "pieces" detachably resting and movable in any direction on the board in 30 playing the game, each piece bearing a character identifying it with respect to a particular line or space of the musical staff.

2. A musical game board having a rectangularly checkered face and a pair of musical staffs near opposite margins of the board, "pieces" detachably resting and 35 movable in any direction on the board in playing the game, each piece bearing a character identifying it with respect to a par-

ticular line or space of the musical staff, 40 and king-rows near opposite margins of the board.

3. A musical game board having a rectangularly checkered face and representations of piano key boards at opposite sides 45 of such checkered face, and "pieces" detachably resting and movable in any direction upon the checkered face in playing the game, each piece bearing a character identifying it with respect to a particular key of 50 the key board.

4. A musical game board having a checkered face, a musical staff near each margin of the board, a piano key board representation adjacent each staff, and "pieces" 55 detachably resting and movable in any direction upon the board in playing the game, each piece having a character identifying it with respect to a particular line or space and 60 a particular key of the respective staff and key board representation.

5. A musical game board having a checkered face, a musical staff near each side of the board, a representation of a piano key board adjacent each of said staffs, a king-row interposed between each musical staff and the adjacent key board representation, and "pieces" 65 detachably resting and movable in any direction upon the board in playing the game, each piece bearing a character identifying it with respect to a particular line or space and a particular key of 70 the respective staff and key board representation.

In witness whereof I hereunto affix my 75 signature.

DOROTHY MILLER.
